UNITED STATES PATENT OFFICE.

WILLIAM MILLER, OF BIRMINGHAM, ENGLAND.

SPRING DRESS-FASTENING.

1,208,612.

Specification of Letters Patent.

Patented Dec. 12, 1916.

Application filed October 15, 1915. Serial No. 55,965.

To all whom it may concern:

Be it known that I, WILLIAM MILLER, subject of the King of Great Britain, residing at 43 St. Oswald's road, Small Heath, in the city of Birmingham, England, engineer, have invented certain new and useful Improvements Relating to Spring Dress-Fastenings, of which the following is a specification.

10 This invention has for its object to provide an improved spring or snap dress fastening which is not liable to injury in such laundry operations as mangling and ironing.

15 The invention comprises the use as one element of the fastening of a flat spring metal ring which can be detachably engaged by a projection from the complementary part of the fastening.

20 The invention further comprises the employment of a pair of similar flat spring metal rings which are detachably engaged by an intermediate connecting piece.

25 Referring to the accompanying sheet of explanatory drawings: Figure 1 is a part sectional elevation of a blouse or like dress fastening constructed in accordance with this invention. Fig. 2 is a front elevation of the member carrying the projection and Fig. 3 a front elevation of the flat spring ring. Fig. 4 is a front elevation of a modified form of spring ring. Fig. 5 is a part 30 sectional elevation of a modified fastening in which two spring rings are employed, and Fig. 6 is a front elevation of one of the rings 35 with the projection attached thereto.

The same reference letters in the different views indicate the same or similar parts.

40 In one construction of a dress fastening as shown in Fig. 1, two principal elements are employed. One is in the form of a flat metal ring *a* which is preferably provided with radial slots *b* terminating in the inner periphery of the ring to impart the required resiliency. Preferably the slots terminate 45 in perforations *c*. Perforations *d* may also be provided for the reception of the stitches whereby the ring is secured to the dress, but the perforations *c* may be used for this purpose. Increased resiliency may be obtained 50 by the addition of slots *e* between the perfora-

rations *d* and the outer periphery as shown in Fig. 4. The stitches are then passed through the perforations *c*.

The other element consists of a narrow circular projection *f* formed with a flange 55 or base *g* which is provided with perforations *h* to permit of its being stitched to the dress. Engagement of the elements is effected by pressing the projection *f* into the spring ring where it is secured by the action 60 of the ring of the projection which is grooved peripherally to prevent accidental detachment. The elements are separated by pulling them apart like an ordinary spring fastening. The projection above described 65 being shallow and of circular form is less liable to crushing than the type of projection usually employed, and the element which it engages is thin and flat so that mangling and ironing can have no injurious effect 70 on it.

In the form shown in Fig. 5 two similar spring rings *a* are employed in conjunction with a connecting piece. The latter comprises a projection *f* formed on each 75 side of a flange *g*. The flange *g* is placed between the rings and each projection engages a ring. In ordinary use one of the projections and one of the rings are never separated. It is immaterial which projection is disengaged from its ring when the dress is unfastened as both projections and rings are similar. Before the dress is submitted to laundry operations the projection is removed from each of the rings, and 80 the two flat rings of each fastening alone are 85 left on the article.

Having thus described my invention what I claim as new and desire to secure by Letters Patent is:—

90 1. A dress fastening comprising only a flat ring, radial slots terminating at the inside of the ring, perforations in the ring for the reception of stitches, a complementary piece and a narrow projection on said piece which can detachably engage the ring, substantially as set forth.

95 2. A dress fastening comprising only a flat ring, radial slots terminating at both the inside and outside of the ring, perfora- 100

tions for the reception of stitches, a complementary piece and a projection on said piece which can detachably engage the ring, substantially as set forth.

3. A dress fastening comprising only a pair of similar flat spring rings, radial slots terminating at the inside of each ring, per-

forations in each ring for the reception of stitches, and a connecting piece which can detachably engage both rings, substantially as set forth.

In testimony whereof I have signed my name to this specification.

WILLIAM MILLER.
